UNITED STATES PATENT OFFICE.

WILLIAM P. CORSON, OF NEW YORK, N. Y.

CUTTER-HEAD FOR HEEL-TRIMMING MACHINES.

SPECIFICATION forming part of Letters Patent No. 331,771, dated December 8, 1885.

Application filed August 19, 1885. Serial No. 174,784. (No model.)

To all whom it may concern:

Be it known that I, WILLIAM P. CORSON, of the city, county, and State of New York, have invented a new and useful Improvement in the 5 **Rotary Cutters for Heel-Trimming Machines;** and I do hereby declare that the following is a full and exact description thereof, reference being had to the accompanying drawings, and to the letters of reference marked thereon, 10 **making a part of this specification.**

My invention relates to the rotary cutter in a heel-trimming machine by which the heels of boots and shoes are exteriorly shaped, and has for its object to provide for a ready adjustment of the tread-guard or tread-rest to cutters 15 of different widths and the prevention of injury to the boot or shoe by reason of its contact with said tread-guard.

In the accompanying drawings, Figure 1 is 20 a side elevation of an adjustable cutter-holder and cutter fitted with my improved tread-guard, and Fig. 2 a central longitudinal section of the same.

A represents the central rotating spindle or 25 hub of the cutter. The enlarged inner end of the spindle is formed with an interiorly-threaded socket, b, by means of which it is attached to the operating-shaft of a heel-trimming machine. Its opposite end is formed with 30 a threaded central recess, c, to receive the central bolt or stud, D, upon which the counter-guard F is fitted. The counter-guard F is by preference mounted upon a sleeve, e, so as to be free to rotate loosely thereon.

The cutter B is preferably made up of a series 35 of disks or plates armed with a series of blades projecting each at an inclination to a radial line, and each so grooved at its outer end as that the periphery of the cutter shall 40 have a molded or curved form longitudinally, (see Fig. 1,) the counterpart or reverse of the curve which it is desired to give to the heel laterally.

G represents the beveled-edge circular disk 45 or radial flange, which is formed or fitted at the inner end of the spindle A to constitute the tread-guard or top-piece rest, which serves to prevent the action of the cutter upon the heel from forcing the tread-lift outward.

The cutting-disks of the cutter, when fitted 50 upon the spindle A, are usually confined thereon between the fixed tread-guard G and the counter-guard F by screwing up the stud or bolt D into its seat e, so that its head shall

carry and force the inner end of the sleeve e 55 against the cutter.

In my invention this guard G, constructed, as usual, in the form of a circular disk, is mounted to revolve loosely upon a collar, i, formed upon the inner end of a sleeve, K, 60 adapted to encircle and screw upon the enlarged inner end of the spindle A, this end of the spindle being exteriorly threaded for the purpose, as illustrated in Fig. 2. The inner end of the collar i bears against the cutter, so that 65 the tread-guard G may not be bound thereby, and the guard is thus left entirely free to revolve after the cutter is fixed upon the hub or spindle A, the cutter being confined between the collar i at one end and the sleeve e at the 70 other by the operation of the bolt D, as described.

The free rotary movement of the tread guard or rest G effectually prevents the injury which oftentimes results from the contact of the tread-surface or top piece of the heel with the ordinary fixed gear, especially when the heel is wet or damp. By turning the sleeve K upon its threaded seat the collar i may be adjusted 80 to and from the opposite sleeve e, (see dotted lines in Fig. 2,) so that cutters of different lengths may be fitted upon the same hub or spindle, A, thereby avoiding the necessity of changing the cutter-head for different sizes or 85 descriptions of heels.

While it is preferable that the guard G shall be made detachable and left free to revolve, it is not essential, and I contemplate the use of the adjustable sleeve K as a device for confining the cutters in position upon the spindle 90 A in whatever manner the guard may be combined or connected therewith.

I claim as my invention—

The combination, in a heel-trimming machine, with its cutter-spindle, the tread-guard 95 at its inner end, the cutter-guard at its outer end, and means, substantially as described, for securing the counter-guard upon the spindle, of an internally-threaded sleeve screwing upon the inner end of the spindle, substantially 100 in the manner and for the purpose herein set forth.

In testimony whereof I have signed my name to this specification in the presence of two subscribing witnesses.
